THROW-OFF MECHANISM FOR ROTARY
OFFSET PRESSES

James R. Wood, Cleveland, Ohio

Continuation of abandoned application Serial No. 46,298, August 26, 1948. This application November 14, 1951, Serial No. 256,244

13 Claims. (Cl. 101—218)

1

This invention relates to improvements in throwoff mechanism for rotary offset press, and has to do particularly with throwoff mechanism for rotary offset printing presses in which tripping of the press causes movement of the blanket cylinder toward or from the plate cylinder and the impression cylinder sequentially.

This application is a continuation of my co-pending application Serial No. 46,298 filed August 26, 1948, and now abandoned.

One of the objects of the invention is the provision of means for accomplishing such sequential operation smoothly and without undue friction.

Another object is the provision of mechanism for this purpose wherein the shaft of the blanket cylinder is mounted in a pair of eccentrics which are in turn mounted in movable bearing blocks with mechanism for actuating the eccentrics first to throw off the blanket cylinder from the plate cylinder and thereafter in the same cycle of the press unit for moving the bearing blocks to throw off the blanket cylinder from the impression cylinder, the same mechanism functioning in the same sequence when impression is to be thrown on, namely to throw the blanket cylinder against the plate cylinder first and against the impression cylinder thereafter.

Other objects and features of novelty will appear as I proceed with the description of that embodiment of the invention which, for the purposes of the present application, I have illustrated in the accompanying drawings, in which

Fig. 1 is a side elevational view, more or less diagrammatic in character, of a unit of a rotary offset printing press embodying the invention, with the cylinders in printing relation.

Fig. 2 is a similar view with the blanket cylinder thrown off from the plate cylinder.

Fig. 3 is a similar view with the blanket cylinder thrown off from both the plate and the impression cylinders.

Fig. 4 is a detail plan view of an adjusting means for the mechanism employed to move the bearing blocks.

Fig. 5 is a detail sectional view taken substantially on the line 5—5 of Fig. 1.

Fig. 6 is a detail elevational view of an adjustable thrust block which may be employed in connection with the invention.

Fig. 7 is a side view of the same, and

Fig. 8 is a sectional view taken substantially along the line 8—8 of Fig. 6.

Referring to the drawings one side member of a press frame is shown fragmentally at 10. In

2

this and the opposite side member, not shown, are journaled the shafts 11 and 12 of the plate and impression cylinders 13 and 14 of a unit of a rotary offset printing press. These cylinders therefore have fixed axes. The blanket cylinder 15 has bearings that are movable first away from cylinder 13 and secondly away from cylinder 14, the throwoff being accomplished sequentially and occurring in each instance while the gaps in the cylinders are passing each other.

At the opposite ends of the blanket cylinder the side frame members are cut away as indicated at 16, and in these openings are oscillatably mounted a pair of like bearing blocks, one of which is shown at 17 in the drawings. The lower end of each of these blocks has a transverse recess 18 of cylindrical contour in which is mounted a bearing pin 19, this pin being secured to the block by a pair of screws 20 which are set into counterbored holes in the pin. A pair of bearing caps 21 secured to the frame by screws 22 hold pin 19 in a cavity 23 of cylindrical contour formed in each of the frame side members. When the block 17 is tilted therefore pin 19 turns in cavity 23 as a bearing. A heavy coil spring 24 bears at one end against an adjustable abutment 25 mounted in the frame and at the other end against an ear 26 which extends upwardly from the bearing block 17. The spring therefore tends to swing the bearing block counterclockwise upon its bearing 19, 23.

The aligned pivot pins 19 for the bearing blocks 17 are located substantially in the plane through the axes of cylinders 13 and 15 on the side of cylinder 15 which is remote from cylinder 13. The opening 16 in each of the frame side members is closed by a bracket 120 which is removably attached to the frame by bolts 121 and 122.

It will be apparent that by removing the screws 22 and the caps 21, the bearing blocks 17 together with the eccentrics 28 mounted therein and the shaft bearings 30 carried by the eccentrics may be withdrawn axially of the cylinder shaft 31 out of the frame 10. When both bearing blocks have been thus removed and the brackets 120 have also been removed the blanket cylinder can be taken out of the machine for conditioning or replacement.

In each of the blocks 17 there is a circular opening 27 in which is mounted an eccentric 28. The circular opening 27 has its center at 29, which therefore is the center of rotation for eccentrics 28. Within each of the eccentrics 28 there is mounted the outer race 30 of a roller

bearing, the inner race of which carries the shaft 31 of blanket cylinder 15. A suitable bearing cap 32 may be attached to the eccentric 28 as shown in Fig. 5.

On the upper side of each eccentric 28 there is an outwardly extending bifurcated ear 33 in which is rotatably mounted a pin 34. A link 35 is adjustably connected with this pin. An eye on one end of link 35 is pivotally connected at 36 with a bifurcated crank 37 that is formed integrally with a yoke 38 which is keyed to a shaft 39 that is mounted in the frame and extends entirely across the press where there is keyed to it another crank 37 connected by a link 35 with an ear 33 on the eccentric at that side of the machine.

Yoke 38 carries the usual pins 9 and 40 and the usual extensions 41 and 42, the latter having adjustable abutment pins 43 that are adapted to engage a stop 44 fixed in the frame member 10. Pins 9 and 40 are adapted to be engaged by the shoulders on a thrust block 45 pivoted at 46 on a lever 47 which is pivotally mounted in the frame at 48. 49 is a control rod pivotally connected with thrust block 45 and adapted to be shifted longitudinally when the unit is to be tripped on or off. Lever 47 carries a follower 50 which runs on a cam 51 that is keyed to shaft 12.

A second follower 52 on a bell crank lever 53 also runs upon cam 51. The other arm of lever 53 carries a pivot 54 upon which is mounted the rear end of a second thrust block 55. A crank 56 on lever 47 carries a wobble pin 57 which is perforated to receive slidably a rod 58, the other end of which is pivoted to a crank 59 on lever 53. A compression spring 60 surrounding rod 58 bears at one end against wobble pin 57 and at the other against a collar 61 on the rod, spring 60 thereby serving the double purpose of holding both of the followers 50 and 52 against the surface of cam 51.

Thrust block 55 embodies the usual shoulders for engagement one at a time with pins 62 and 63 on a yoke 64 keyed to a shaft 65 which extends entirely across the machine. Yoke 64 also carries extensions 66 and 67 with adjustable abutment pins 68 for engagement with a stop 69 fixed in the machine frame. A bifurcated crank 70 is integral with yoke 64 and carries an oscillatable pin 71 to which is secured a link 72, at the upper end of which there is an eye that is mounted upon a pivot 73 in the outer end of a crank arm 74 that is keyed to a short shaft 75. Shaft 75 is journaled in an eccentric sleeve 76 mounted in bracket 120 in the periphery of which sleeve are worm wheel teeth 77. A worm 78 carried upon an upright shaft 79 journaled in bracket 120 meshes with worm wheel teeth 77 and may be turned thereby for adjustment purposes. A gauge plate 80 keyed to shaft 79 indicates the degree of adjustment. Parts numbered 70 to 80 inclusive are duplicated on the opposite side of the machine, and the gauge plates assist materially in maintaining the adjustment equal.

The inner side of each of the eccentrics 76 is cut away as indicated at 81 in Fig. 4 to expose shaft 75, and that shaft is recessed to provide a curved socket 82 which receives one end of a link 83 shaped somewhat like a dumb-bell. The rounded extremity of the opposite end of this link bears against the wall of a curved recess 84 formed in the adjacent side of the bearing block 17. The center of shaft 75 is located at the point 85. The centers of curvature of the two extremities of link 83 are marked 86 and 87. It will be observed that a toggle connection is thus set up with one arm

extending from point 85 to point 86 and the other arm extending from point 86 to point 87. When the points 85, 86, 87 are in line, as in Fig. 1, the connection is "on toggle." In practice the point 86 may be carried slightly above the line between points 85 and 87 to an over-center position for the sake of stability. The center of eccentric 76 is at 88. Obviously as the worm 78 is turned in one direction or the other the center 85 of shaft 75 moves inwardly or outwardly, and thus the outer extremity of the toggle connection is adjusted toward or away from the bearing block 17.

When the toggle is in toggle on position, as shown in Fig. 1, pressure is exerted against the bearing blocks 17 along the line of centers between points 85 and 87, which line cuts across the plane of the axes of cylinders 13 and 15 at a point intermediate the axes of these cylinders which is disposed at a considerable distance from the axis of pin 19.

On the pin 40 carried by yoke 38 there is pivotally mounted a bracket 90 which has a bifurcated arm straddling pin 9. On this bracket there is an arm 91 to which is pivoted a rod 92 that extends through a sleeve 93 that is slidable upon the rod and is yieldably held in position by two coil springs 94 and 95 backed by collars 96 and 97 fixed to the rod. Lever 98 is mounted to turn upon a pivot 99 fixed in thrust block 55. Its opposite end is pivotally connected at 100 with sleeve 93.

Thrust block 55 carries a pair of integral projecting walls 101. An eccentric head 102 on one end of a shaft 103 fits between these walls. Head 102 bears against one surface of lever 98 and a collar 104 fixed to shaft 103 bears against the other surface of the lever. Two ears 105 and 106 extending laterally from the lever carry stop pins 107 and 108. Handle 109 is mounted in shaft 103 in a position to contact pin 107 or 108 at opposite extremes of its movement. Shaft 103 and handle 109 together may be termed a crank, by means of which eccentric 102 is turned to shift lever 98 on one or the other of the pivots 99 or 100 as a center. Since the lever is connected with thrust block 55 by pivot 99, the swinging of lever 98 on pivot 99 from one extreme position to the other in turn swings thrust block 55 upon its pivot 54.

Operation.—Assuming that the unit is in printing condition, as illustrated in Fig. 1, and that a throwoff of the unit is called for, control rod 49 will then be moved toward the right, which will swing thrust block 45 over into contact with pin 40 on yoke 38. When the high spot of cam 51 engages follower 50, as in Fig. 2, a shoulder on thrust block 45 working against pin 40 will turn yoke 38 counterclockwise along with shaft 39, breaking the toggle 37, 35 and turning the eccentrics 28 clockwise about their axis 29. The center of shaft 31 and of blanket cylinder 15 will thus be swung through a small fraction of an inch in a direction downwardly and toward the left. It will be understood that all of the cylinders 13, 14 and 15 are provided with gears at the side of the machine not illustrated herein and that the gear on cylinder 15 meshes with the gears on both of the cylinders 13 and 14. The gears remain in mesh when cylinder 15 is thus thrown off from plate cylinder 13, and since the relative movement of the gears on cylinders 15 and 14 is substantially tangential when the throwoff from cylinder 13 takes place, the contact between cylinders 15 and 14 is not affected.

When thrust block 45 swings from the position of Fig. 1 to that of Fig. 2 and turns yoke 38 and

bracket 90 counterclockwise to the position of Fig. 2, rod 92 exerts a pull on lever 98 which is communicated through eccentric head 102 and pivot 99 to thrust block 55, swinging that block to the right as indicated in Fig. 2. When the high spot of cam 51 reaches follower 52, as shown in Fig. 3, thrust block 55 is moved longitudinally toward the left, swinging yoke 64 and shaft 65 counterclockwise, which exerts a downward pull on each of the links 72 and functions through cranks 74 to turn shafts 75 clockwise, thereby breaking each of the toggle connections of which dumb-bell link 83 is one arm. With the breaking of the toggle connections springs 24 act to swing bearing blocks 17 upon pins 19 as pivots. The center of shaft 31 therefore swings away from cylinder 14 a small fraction of an inch. In this case the relative travel of the gears on cylinders 13 and 15 is substantially tangential, and is easily permitted by the fact that they are then meshing loosely due to their previous separation. These two motions of cylinder 15 in the throwoff first from cylinder 13 and then from cylinder 14 occur in the same cycle of the press. The throwoff from the impression cylinder 14 occurs while gaps G¹ and G² of the plate and blanket cylinders are passing each other, the throwoff having been completed at the time in the cycle depicted in Fig. 2. The throwoff from the impression cylinder 14 occurs while the gaps G² of the blanket cylinder and G³ of the impression cylinder are passing each other, having been completed at the point illustrated in Fig. 3. The printing of a sheet passing the impression line between cylinders 15 and 14 is completed after the throwoff from cylinder 13 and before the throwoff from cylinder 14.

When the feeding of sheets is resumed after a short interruption, control rod 49 is moved toward the left from the Fig. 3 position to the Fig. 1 position, causing the yoke 38 to turn clockwise and the toggle connections 37, 35 to assume the "on toggle" position of Fig. 1, which turns eccentrics 28 counterclockwise for throwing the blanket cylinder into printing engagement with plate cylinder 13. At the same time that yoke 38 turns clockwise rod 92 is pushed down and toward the left, operating through lever 98 and eccentric head 102 to swing thrust block 55 toward the left into the position of Fig. 1, where it is ready to be acted upon by cam 51 for turning yoke 64 clockwise from the Fig. 3 position to that of Fig. 1. This motion of yoke 64 is transmitted through crank 70 and link 72 to crank 74, shifting the toggle connection center 86 up into line with the centers 85 and 87 to bring the parts of the toggle connection to the "on toggle" position against the action of compression spring 24, thereby throwing the blanket cylinder into operative engagement with the impression cylinder.

When the toggle 35, 37 is put into toggle-on position, as illustrated in Fig. 1, for throwing the blanket cylinder 15 into operative position with respect to plate cylinder 13, the reaction from the force necessary to press cylinder 15 upwardly against cylinder 13 is taken largely by the bearing block pins 19. Consequently there is friction of rest between the pins and the bearing caps 21, which must be overcome in shifting the cylinder 15 sequentially into printing relation with impression cylinder 14. The means disclosed herein for overcoming this friction and pressing the cylinder 15 against the cylinder 14 or the paper passing between these

cylinders possesses considerable mechanical advantage. In the first place there is mechanical advantage in the length of lever arm 74 as compared with the short arm of the toggle, namely that between points 85 and 86, and in the second place there is the mechanical advantage gained from the length of the arm between the axis of pivots 19 and the point at which force is applied to the bearing blocks 17 as compared with the radius of pivots 19.

While as shown herein the pivots 19 are so disposed as to provide for the swinging of the bearing blocks toward or away from the impression cylinder, it will be appreciated that the pivots could be so disposed as to provide for swinging the bearing blocks toward or away from the plate cylinder, the eccentrics 28 then functioning to move the blanket cylinder toward or away from the impression cylinder.

When a run of printing is to be started or is to be resumed after a period of idleness, it is necessary to ink up the blanket by several passes over the form on cylinder 13 before sheets are fed through the impression line between cylinders 14 and 15. For this purpose it should be possible to throw the blanket cylinder onto the plate cylinder while separation of the blanket cylinder from the impression cylinder is maintained. This is accomplished in the present invention by the mechanism illustrated in detail in Figs. 6, 7 and 8. When it is desired to start the unit under these conditions, the handle 109 is thrown from the position illustrated in Figs. 1, 2 and 3 to the position illustrated in Fig. 6. The eccentric head 102 is thus turned through slightly more than 180 degrees. Since the thrust block 55 bears at this time against pin 63 and pivot 99 is fixed in the thrust block the turning of eccentric head 102 cannot move pivot 99 bodily. Consequently the opposite end of the lever 98 must yield, and this results in sliding the sleeve 93 on rod 92 toward the left, compressing spring 94. Now the operator causes control rod 49 to move toward the left, throwing thrust block 45 against pin 9, whereupon cam 51 operates through follower 50, bell crank 47 and thrust block 45 to swing yoke 38 clockwise and bring the toggle 37, 35 to "on toggle" position for throwing the blanket cylinder onto plate cylinder 13. As yoke 38 turns clockwise rod 92 is forced downwardly and toward the left, thereby moving collar 96 away from sleeve 93 and reducing the compression of spring 94 somewhat. This downward movement of rod 92 is not sufficient to move thrust block 55 from its Fig. 3 position however and therefore the toggle connection which includes dumb-bell link 83 remains in the "off toggle" position and the blanket cylinder is not thrown over into engagement with impression cylinder 14.

When the blanket is properly inked the operator, who has meanwhile been manually holding control rod 49 toward the left in the "impression on" position, releases the latter rod so that cam 51 operates through lever 47 and thrust block 45 to swing yoke 38 counterclockwise and throw blanket cylinder 15 away from plate cylinder 13. The counterclockwise movement of yoke 38 moves rod 92 to the right to the position shown in Fig. 3, increasing the compression of spring 94. Thereafter the operator throws handle 109 back to the position illustrated in Figs. 1, 2 and 3 which causes lever 98 to swing about pivot 99 and move sleeve 93 toward the right to its normal position in which the springs 94 and 95 are free to swing the thrust block to either of its operative posi-

tions under the control of rod 92. When normal conditions are thus restored, the feeding of sheets may be started and the pressure between the cylinders thrown on or off in sequence in the manner described under the control of rod 49.

Having thus described my invention, I claim:

1. In a rotary offset printing press, a frame, a printing unit comprising a plate cylinder, an impression cylinder and a blanket cylinder, said blanket cylinder having a shaft the axis of which is disposed to one side of the plane through the axes of the plate and impression cylinders, a pair of like bearing blocks movably mounted in said frame at the opposite ends of the blanket cylinder, a pair of like eccentrics rotatably mounted in said bearing blocks, said blanket cylinder shaft being mounted in said eccentrics, a cam rotating once for each press cycle, mechanism operatively associated with said cam for turning said eccentrics, a control settable for causing said cam to actuate said mechanism to impression off position, a second mechanism operatively associated with said cam for moving said bearing blocks, and a control responsive to actuation of said first mechanism to impression off position for setting said second mechanism in position to be actuated by said cam later in the cycle for moving said bearing blocks to impression off position.

2. In a rotary offset printing press, a frame, a printing unit comprising a plate cylinder, an impression cylinder and a blanket cylinder, said blanket cylinder having a shaft the axis of which is disposed to one side of the plane through the axes of the plate and impression cylinders, a pair of like bearing blocks at the opposite ends of the blanket cylinder, mounted in said frame to swing about a common axis parallel with the axis of the blanket cylinder, a pair of like eccentrics rotatably mounted in said pair of bearing blocks, said blanket cylinder shaft being mounted in said eccentrics, a cam rotating once for each press cycle, mechanism operatively associated with said cam for turning said eccentrics, a control settable for causing said cam to actuate said mechanism to impression off position, a second mechanism operatively associated with said cam for swinging said bearing blocks, and a control responsive to actuation of said first mechanism to impression off position for setting said second mechanism in position to be actuated by said cam later in the cycle for swinging said bearing blocks to impression off position.

3. Mechanism as defined in claim 2, characterized in that during operation of the press the common axis of said bearing blocks is disposed approximately in the same plane with the axes of said plate and blanket cylinders and the axis of said eccentrics is disposed approximately in the same plane with the axes of said blanket and impression cylinders.

4. Mechanism as defined in claim 2, comprising means settable in advance for disabling said second control.

5. In a rotary offset printing press, a frame, a printing unit comprising a plate cylinder, an impression cylinder and a blanket cylinder, said blanket cylinder having a shaft the axis of which is disposed to one side of the plane through the axes of the plate and impression cylinders, a pair of like bearing blocks at the opposite ends of the blanket cylinder mounted in said frame to swing together about a common axis parallel with the axis of the blanket cylinder, a pair of like eccentrics rotatably mounted for movement together

in said pair of bearing blocks, said blanket cylinder shaft being mounted in said eccentrics, mechanism for turning said eccentrics comprising a pivoted yoke, a crank integral therewith and

5 a thrust block swingable into operative relation with either end of said yoke, and a link pivotally connected with said crank and one of said eccentrics, mechanism for swinging said bearing blocks comprising a pivoted yoke, a crank integral therewith and a thrust block swingable into operative relation with either end of said yoke, and an operative connection between said crank and one of said bearing blocks, a connection between the first named yoke and the second named thrust block for swinging the latter from one operative position to the other, and cam means for reciprocating said thrust blocks one at a time, whereby the turning of said eccentrics results in the setting of the thrust block for swinging said bearing blocks.

6. In a press unit of the character described, a pivoted thrust block having two operative positions angularly separated, a lever, a pivot connecting one end of said lever with said thrust block, a crank oscillatably mounted in said lever at an intermediate point of the latter, an eccentric head connection between said crank and said thrust block, and a reciprocable operating rod, a sleeve slidable thereon articulated with the opposite end of said lever, springs on said rod bearing against the opposite ends of said sleeve, the endwise movement of said rod being normally adapted to shift said block from one operative position to the other, the turning of said crank to move said eccentric head through a predetermined angle swinging said lever about its pivot and shifting said slide to increase the pressure of one of said springs and decrease that of the other, whereby movement of the rod thereafter in one direction merely equalizes the spring pressure and leaves the thrust block unaffected.

7. Mechanism as defined in claim 6, comprising a pair of stops on said lever to limit the throw of said crank in opposite directions.

8. In a press unit of the character described, a pivoted thrust block member having two operative positions angularly separated, a lever member, a pivot connecting said lever member with said thrust block member, a crank oscillatably mounted in one of said members, an eccentric head on said crank engaging abutments on the other of said members, a reciprocable rod, a sleeve slidable thereon, springs on the rod bearing against opposite ends of said sleeve, the endwise movement of the rod being adapted when said crank is in one position to shift the thrust block from one operative position to the other, the movement of said crank to its opposite position shifting said sleeve to increase the pressure of one of said springs and decrease that of the other, whereby the movement of said rod thereafter in one direction affects merely the pressure of said springs and leaves said thrust block unaffected.

9. In a press unit of the character described, a pivoted thrust block having two operative positions angularly separated, an operating rod movable lengthwise transversely of the block and parallel to the plane in which it is adapted to swing, a sleeve slidable on said rod, compression springs on said rod bearing against opposite ends of said sleeve tending to hold said sleeve in a predetermined position on said rod, a lever having an articulated connection with said sleeve, a pivot connecting said lever with said thrust block, and

means for swinging said lever on its pivot to shift said sleeve for compressing one of said springs, whereby when the thrust block is held against movement in one direction the actuation of said operating rod in the opposite direction merely relieves the compression of said last named spring and transmits no motion to said thrust block.

10. In a press unit of the character described, a pivoted thrust block having two operative positions angularly separated, a lever, a pivot connecting said lever with said thrust block, a reciprocable operating rod adapted to shift said block from one operative position to the other, a sleeve slidable thereupon, compression springs on said rod bearing against opposite ends of said sleeve tending to hold said sleeve in a predetermined position on said rod, an articulated connection between said sleeve and one end of said lever, means for swinging said lever on its pivot to shift said sleeve for compressing one of said springs and a stop adapted to prevent movement of the thrust block in one direction, movement of said rod thereafter in a direction tending to move the thrust block away from said stop results merely in relieving the compression of said last named spring.

11. In a rotary offset printing press, a frame, a printing unit comprising a blanket cylinder and plate and impression cylinders cooperating therewith, said blanket cylinder having a shaft the axis of which is disposed to one side of the plane through the axes of said cooperating cylinders, a pair of bearing blocks at the opposite ends of the blanket cylinder, in which the cylinder shaft is mounted, openings in the frame of a size to clear said blocks, aligned pivots parallel to the cylinder shaft spaced radially from said shaft upon which said blocks are mounted to swing bodily to throw said blanket cylinder toward or away from one of said cooperating cylinders and removable means for holding said blocks against movement axially of said pivots, whereby upon release of said last named means one of said blocks may be moved outwardly through the opening in that side of the frame.

12. In a rotary offset printing press, a frame, a printing unit comprising a blanket cylinder and plate and impression cylinders cooperating therewith, said blanket cylinder having a shaft the

axis of which is disposed to one side of the plane through the axes of said cooperating cylinders, a pair of like bearing blocks at the opposite ends of the blanket cylinder, bearings for the blanket cylinder shaft in said blocks, openings in the frame of a size to clear said blocks, aligned pivots parallel to the cylinder shaft spaced radially from said shaft upon which said blocks are mounted to swing bodily to throw said blanket cylinder toward or away from one of said cooperating cylinders and removable means for holding said blocks against movement axially of said pivots, whereby upon release of said last named means one of said blocks with its shaft bearing may be moved outwardly through the opening in that side of the frame.

13. In a rotary offset printing press, a frame, a printing unit comprising a blanket cylinder and plate and impression cylinders cooperating therewith, said blanket cylinder having a shaft the axis of which is disposed to one side of the plane through the axes of said cooperating cylinders, a pair of like bearing blocks at the opposite ends of the blanket cylinder, aligned pivots for said bearing blocks carried by said frame, a pair of like eccentrics rotatably mounted in said bearing blocks, said blanket cylinder shaft being mounted in said eccentrics, means for turning said eccentrics to throw said blanket cylinder into printing relation with said last named cooperating cylinder, means for applying pressure to said blocks for swinging said blanket cylinder about said pivots into printing relation with the other of said cooperating cylinders, said frame being provided with openings for said blocks such that the blocks may be removed from the blanket cylinder shaft by a movement along the axis of said shaft, and removable means for holding said blocks against movement axially of said pivots.
